CLAIM

The ornamental design for an escrow box for coin operated machines, substantially as shown and described.

DESCRIPTION

FIG. 1 is a top perspective view of an escrow box for coin operated machines, showing my new design;

FIG. 2 is a top plan view thereof;

FIG. 3 is a left side elevational view thereof, the right side being a mirror image thereof;

FIG. 4 is a bottom plan view thereof; and

FIG. 5 is an end view thereof, the opposite end being a mirror image thereof.
